UNITED STATES PATENT OFFICE.

LINNAEUS E. BAKER, OF FORT WAYNE, INDIANA, ASSIGNOR TO WAYNE OIL TANK AND PUMP COMPANY, OF FORT WAYNE, INDIANA, A CORPORATION OF INDIANA

PUMP.

1,324,294.

Specification of Letters Patent.

Patented Dec. 9, 1919.

Application filed November 28, 1916. Serial No. 133,904.

To all whom it may concern:

Be it known that I, LINNAEUS E. BAKER, a citizen of the United States, residing at Fort Wayne, in the county of Allen and State of Indiana, have invented new and useful Improvements in Pumps, of which the following is a specification.

My invention relates to the class of reciprocating-piston pumps intended to produce a constant flow; its object being to produce a structure embodying such parts and such functional relation of parts as that—

(1) The quantity of liquid delivered shall accurately correspond with and be regulated by the quantum of partial or entire revolution or revolutions of the crank-shaft employed in reciprocating the pistons;

(2) The crank movement within pre-determined limits shall be the means of pumping, measuring and indicating the quantity of liquid delivered;

(3) The pumping mechanism shall embody means of regulating with accuracy, and, if desired, registering,—the exact amount of liquid delivered, according to a standard of measurement adopted, adjustable relatively to the increments of rotation of the crank-shaft;

(4) The structure as a whole shall be simple, compact, self-contained, and operable with facility by hand or otherwise as a means of supplying the public need as occasion may require; and be, moreover, strong, durable and easily maintained in working order.

To these and other incidental ends, my invention consists in the embodiment of principles of structure and operation as exhibited in the mechanism and apparatus herein described, and shown in the drawings accompanying and forming part of this specification, showing the best form in which I have contemplated the application of the principles involved in the invention.

45 In the drawings hereto attached:

Figure 1 is a perspective elevation of the device complete;

Fig. 2, a vertical axial section in a plane parallel with the plane of the cam; and

50 Fig. 3, is a section taken on the line 3—3 of Fig. 2 looking in the direction of the arrow. The upper portion of the cam cut by this plane is not shown in section.

Fig. 4, is a section taken on the line 4—4 of Fig. 2 looking in the direction of the arrow, the rockshaft being shown full, and crank arms shown attached thereto.

Referring now to the drawings, the main body, A, of the apparatus is a pump-barrel in which reciprocate two annular plungers, B, arranged one above the other, each plunger being provided with a check-valve, b,—the liquid column being lifted by the plunger temporarily under load passing through the check-valve opening of the plunger not under load; and thus alternating.

The pump barrel, A, is preferably formed of two duplicate open ended cylinders, a, a, seated tandem one upon the other, each provided with a replaceable lining, a¹, in each of which a plunger, B, operates, carrying a lift or check-valve, b, seating upon the inner margin of the annulus and controlling the central opening. The valve has a central upward stem, b¹, guided through a central boss of the valve crib, b², springing from opposite sides of the annulus and terminating in a fork, b³, for a pivotal connection with an operating arm to be described later. Coiled about the stem b¹, under the yoke, a spring, s, holds the valve normally to its seat.

The upper and lower ends of the pump barrel, A, are closed by caps, a², a³, respectively, each being pierced for pipes through which the liquid enters and discharges; and the lower cap, a³, is extended as a base upon which the entire structure rests. Rods, r, connecting the upper and lower caps and base hold all parts firmly together.

Each duplicate part, a, of the pump barrel is formed with a semi-cylindrical enlargement, a⁴, open interiorly; and the sides of each enlargement are oppositely pierced for the reception, at one side of a threaded cap, a⁵, and at the other side for one end of a rockshaft, C, D, respectively, each of which carries, within the enlargement, a crank arm, c¹, d¹, respectively, each extending to and engaging pivotally the fork, b³, of its contiguous plunger, B. Thence outwardly, each rockshaft extends through a stuffing box, located in the side wall of the enlargement and thence through a sleeve, a⁶, said sleeve constituting both a gland for

the stuffing box and a bearing for the rock shaft. The sleeve, in addition to being seated as a gland in the stuffing box in the side wall of the enlargement is also supported in 5 a bracket, a^1 , exterior thereto. A removable bearing, e , secured upon a plate extension, e^1 , of the pump barrel supports the exterior end of the rockshaft. Secured to 10 the outer extremity of each rockshaft is a crank arm, c^2 , d^2 , respectively, for a purpose presently to be described.

Midway between the two enlargements, a^4 , of the pump barrel, A, is a laterally elongated bracket sleeve, f , constituting a 15 bearing and support for a driving shaft, F, which, at one extremity carries—(at the side of the pump-barrel opposite the arms, c^2 , d^2)—a hand crank, f^1 ; and at the other extremity and externally adjacent to said. 20 crank arms c^2 , d^2 , carries a cam plate G. This cam plate is provided at its inner side with a recessed cam-track, g , in which ball-bearing rollers, c^3 , d^3 , of the said crank arms engage at points diametrically opposite 25 site the axis of rotation of the cam—which is the axis of the driving shaft, F.

The cam plate, G, is somewhat oval, the form being determined by the necessary curvilinear eccentricity of the track, g . The 30 plate is attached by screws or bolts, g^1 , to a disk or crank arm, f^2 , fixedly secured to the extremity of the driving shaft, F. The bolts are located upon the same diameter of the disk f^2 , and pass through perforations 35 elongated in the same diameter to permit adjustments of the cam to greater or less eccentricity, to vary correspondingly the length of stroke of the plungers, B, thereby varying the quantity of liquid pumped in 40 the same proportion, in relation to the increments of rotation—the action of the cam being transmitted through the ball-bearing rollers c^3 , d^3 , and crank arms c^2 , d^2 , to the rock shafts, C, D, respectively, and thence 45 by the crank arms, c^1 , d^1 , to the pump plungers, B.

The axes of the rock shafts, C, D, and driving shaft, F, are arranged parallel, equi-distant, and in a common plane which 50 is parallel with the axis of the pump barrel; and, as already explained, the points of engagement of the ball-bearing rollers, c^3 , d^3 , with the cam-track, g , are in diametric relation opposite the cam axis of rotation. It 55 will be obvious, therefore, that each entire revolution of the cam produces a complete double stroke of each plunger, B, in opposite directions, each to the other, by reason of the duplicate connections of the plungers with the common cam-track, but at 60 180 degrees apart.

Taking advantage of these conditions, I so plot the cam track as to overlap these opposite strokes, so that each plunger begins its load stroke before the other has

quite finished its load stroke and the return stroke in each case is accelerated. Thus the liquid column is always under the lifting action of one or both plungers; and the normal weakening of the stroke action toward 70 the beginning and end of the lifting stroke is eliminated by reinforcing each plunger by the other at such periods, and a uniform and constant flow results in quantity exactly proportional to the increments of revolution or revolutions.

The mode of operation has been already sufficiently indicated. A continuous revolution of the crank shaft produces a continuous flow of liquid. Whatever ratio between revolution and output is adopted—according to the adjustable limitations of the structure—fractions of a revolution will produce corresponding fractions of the standard output per revolution. The use 85 of a fixed annular scale (not shown) concentric with the driving shaft and adjacent to the crank arm, f^1 , renders it easy to regulate the limit of movement as desired.

It will be noted also that the body of the 90 pump consisting of the two duplicate cylinders in tandem relation upon a common base, constitutes a support and bearing for the entire system of moving parts, and the whole constitutes a complete entity easily 95 transportable, equipped for instant use.

While I regard the single pump barrel and single cam operating two tandem plungers as the best and simplest form of my invention, it will be obvious that the principle 100 may be embodied in other forms,—as by duplicating pump barrels, or cams, or both. The principle may also be applied to a plurality of plungers operated in gangs in an extended tube to raise a liquid to abnormal heights; but these I regard as within the spirit and purpose of my invention together with mere structural variations.

I claim as my invention and desire to secure by Letters Patent of the United 110 States:—

1. In a pumping apparatus the combination and arrangement of a pump barrel utilized as a support, two lift plungers operating in independent zones; a crank shaft connection for each said plunger in a contiguous zone and having external bearings; an exterior cam and shaft arranged between said crank shafts; and an operative crank arm for each crank shaft separately engaged by said cam.

2. A pumping mechanism embodying a pump-barrel; reciprocating plungers therein, in series; a rock shaft for each plunger journalized on the pump barrel as a support, 115 and extending partly within and partly without the pump barrel area; crank arms upon the rock shafts within and without the barrel area, those within being operatively connected with the plungers; a driving shaft 120

and an operating cam journaled on said pump barrel connecting with the outer arms of the rock shafts.

3. A lift pump, embodying a pump barrel; two plungers in series; mechanism connecting said plungers operatively with a cam; and a rotatable eccentric cam having a side slot with opposite operative surfaces and a contour adapted to reciprocate both 10 plungers simultaneously with diverse and overlapping strokes to equalize and render the flow and delivery of liquid uniform and definitely correspondent with the quantum of rotation of the cam.
- 15 4. In a pump of the character indicated, a pump-barrel; two plungers in series therein; a rotatable eccentric cam adapted to operate, overlap and equalize the strokes to produce uniform flow and delivery, said cam 20 being also adjustable in eccentricity to regulate the quantity delivered at each revolution of the cam; and operative mechanism connecting the cam and plungers.
- 25 5. In a cam-operated pump of the character indicated a pump barrel consisting of two duplicate sections, each having a zone adapted to the complete operation of its plunger and an adjacent zone for the complete operation of its immediate operating 30 connection; and each said last mentioned zone provided with an external enlargement of its inclosure, constituting bearings for external connections to the operating cam.
- 35 6. In a pump of the character indicated, a pump barrel, two duplicate units adapted to

seat in tandem relations, each provided with a lateral opening for convenience in assembling and an external cover for the same, provided with bearings for a rock shaft carrying a crank arm within the cover for 40 the operation of a plunger within the pump barrel.

7. The combination of a pump barrel; two reciprocating plungers therein; two rock-shafts and an intermediate driving shaft arranged in bearings upon the pump barrel equi-distant and in a common axial plane parallel with the axis of the pump barrel; an operating cam upon the driving shaft; and crank arms upon the rockshafts connecting at one side with the pump plungers and at the other with the operating cam.

8. In a pump of the character indicated, having two plungers in series, in combination with an eccentric operating cam having 55 a single continuous cam track, two rock-shafts in bearings at opposite sides of the cam shaft, and having arms connected at one side with the plungers, and at the other with the cam track at diametrically opposite 60 sides of the axis of rotation all mounted on the pump barrel as a support.

In testimony whereof I have hereunto set my hand in presence of two subscribing witnesses.

LINNAEUS E. BAKER.
